CLAIM

The ornamental design for a rotary electrical connector, as shown and described.

DESCRIPTION

FIG. 1 is a top, front perspective view of a rotary electrical connector, showing my new design;

FIG. 2 is a top plan view thereof;

FIG. 3 is a side elevational view thereof, the opposite side being a mirror image;

FIG. 4 is a bottom plan view thereof;

FIG. 5 is a rear elevational view thereof;

FIG. 6 is a front elevational view thereof.
